UNITED STATES PATENT OFFICE.

HENRY W. STAPLES, OF SACO, MAINE.

IMPROVEMENT IN LAMP-FILLERS.

Specification forming part of Letters Patent No. 95,948, dated October 19, 1869.

To all whom it may concern:

Be it known that I, HENRY W. STAPLES, of Saco, in the county of York and State of Maine, have invented a new and Improved Lamp-Filler; and I do hereby declare that the following is a full, clear, and exact description thereof, which will enable others skilled in the art to make and use the same, reference being had to the accompanying drawings, forming a part of this specification.

This invention relates to a new and useful improvement in vessels for filling lamps; and it consists in an air-tube attached thereto and arranged as will be hereinafter more fully described.

In the accompanying sheet of drawings, Figure 1 represents a sectional side view of a lamp-filler provided with one of my air-tubes. Fig. 2 is a top view of the same.

Similar letters of reference indicate corresponding parts.

A represents the vessel or lamp-filler. B is the discharge-tube. C is the air-tube, the ar-

rangement of which on the vessel forms my invention. This tube is attached to the body of the can, just below the cap D, and enters the discharge-tube B at the angle E. From the angle E it extends to near the discharge-nozzle, as seen at f.

In experimenting with lamp-filers I have found that by arranging the air-tube in this manner the best result is obtained, while the air-tube acts as a brace to the spout.

Having thus described my invention, what I claim as new, and desire to secure by Letters Patent, is—

The tube C, attached at one end to the discharge-nozzle B, and at the other to the top of the can A, at a point farthest, or nearly so, from the angle of said nozzle, substantially as herein shown and described, for the purpose specified.

HENRY W. STAPLES.
